FLUID PRESSURE BRAKE DEVICE

Thomas H. Thomas, Edgewood, Pa., assignor to
The Westinghouse Air Brake Company, Wil-
merding, Pa., a corporation of Pennsylvania

Original No. 1,533,481, dated April 14, 1925, Serial
No. 630,686, April 9, 1923. Application for re-
issue November 19, 1926, Serial No. 149,548

56 Claims. (Cl. 303—18)

This invention relates to a fluid pressure brake application controlling device, and more particularly as applied to an automatic train speed control equipment.

5 It is a well known fact that long trains can be handled more smoothly by means of a graduated rather than a continuous application of the brakes, since there is danger when a heavy continuous brake pipe reduction is made that the 10 brakes will be applied at the head end of the train sufficiently in advance of those at the rear end as to cause the slack of the train to run in harshly and thus produce dangerous shocks and possibly a break-in-two on the recoil. The recommended practice for manipulating the brakes 15 on a long train in order to overcome this difficulty, consists in first making an initial light brake pipe reduction, such as to insure that all the brakes on the train will apply, and then after 20 moving the brake valve handle to lap position and holding the same there until the brake pipe exhaust ceases, to effect a heavier brake pipe reduction sufficient to produce the desired application of the brakes.

25 The principal object of my invention is to provide means for accomplishing automatically what is accomplished by the engineer manipulating the brake valve as above stated.

In the accompanying drawings; Fig. 1 is a 30 diagrammatic view, in section, of a brake application controlling device embodying my invention and showing the parts in normal release position; Fig. 2 a similar view, showing the parts in brake application position, as initially assumed; Fig. 3 a sectional view of the pilot valve mechanism shown in Figs. 1 and 2 and in a position assumed after a period of time; Fig. 4 a 35 sectional view of the pilot and hold back valve mechanism of Figs. 1 and 2, showing the parts in position to effect the second reduction in brake pipe pressure; and Fig. 5 a diagrammatic view, showing my invention associated with a signal and speed control equipment.

A desirable application of my invention in 40 connection with an automatic train speed control equipment where the application of the brakes is automatically effected through the operation of the automatic speed control equipment, independently of the engineer, and in the drawings 45 I have shown my invention as applied to an automatic speed control equipment of which the application valve device functions and is controlled identically with the application valve device of my prior Patent No. 1,523,462, issued 50 January 20, 1925.

As shown in the drawings, the equipment may comprise a brake application valve device, the operation of which is controlled by an automatic speed control apparatus (not shown). Said valve device may comprise a casing 1 having a piston chamber 2 connected to a speed control pipe 57, through which the fluid pressure in piston chamber 2 is varied according to the operation of the speed control apparatus. A piston 3 contained in piston chamber 2 is adapted to operate a slide 10 valve 4, contained in valve chamber 5 which communicates through passage 6 with a source of fluid under pressure, such as the main reservoir 7.

Associated with the application valve device is an equalizing discharge valve mechanism comprising a casing 8 containing a piston 9 having the chamber 10 at one side connected by a passage 11 with an equalizing reservoir 12 and the chamber 13 at the opposite side with the usual train brake pipe 14. Said piston is adapted to 20 operate a discharge valve 15 for venting fluid from the brake pipe 14 to effect a reduction in brake pipe pressure and thus cause an application of the brakes in the well known manner.

The mechanism for automatically effecting the 25 split or two application feature of my invention may comprise a casing 16 containing a pilot valve mechanism and a hold back valve mechanism. The pilot valve mechanism may comprise a hollow piston 17 having the piston chamber 18 at 30 the closed end of the piston connected to a passage 19 which leads to the seat of application slide valve 4 and which is also connected to a timing reservoir 20.

In the open end of the piston 17 is mounted a 35 collapsible piston 21 having a longitudinal slot for receiving a pin 22 which is secured to piston 17. Interposed between the closed end of piston 17 and the collapsible piston 21 is a coil spring 23. The piston 21 carries a valve 24 for controlling communication from a chamber 25 to an atmospheric vent port 26, which port also communicates with an intermediate chamber 27.

The hold back valve mechanism may comprise a hollow piston 28 having a seat 29 at one end for 45 engaging a seat ring 30. The inner seated area of the seat 29 is connected by a passage 31 with a second reduction reservoir 32 and the outer seated area is connected by a passage 33 with a first reduction reservoir 34. A spring 35 tends to 50 maintain the piston 28 seated at the right and movement of said piston to the left is adapted to operate a valve 36 through engagement with a stem 37. The left hand end of piston 28 is flared to form a seating ring 39 which is adapted to en- 55

gage a seat upon movement of piston 28 to the left.

In operation, the valve chamber 5 of the application valve device is charged with fluid under pressure from the reservoir 7 by way of passage 6 and fluid from valve chamber 5 equalizes into the piston chamber 2 through a restricted port 40 in piston 3, thus permitting the spring 41 to hold the piston 3 in its normal release position, so long as the control pipe 57 remains closed. Fluid from the brake pipe 14 flows to the chamber 13 of the equalizing discharge piston 9 and through a passage 42, past a check valve 43, a cavity 44 in slide valve 4, and a passage 45 to the piston chamber 10. From passage 45 fluid also flows through passage 11 to the equalizing reservoir 12, charging same to the pressure carried in the brake pipe 14.

The first reduction reservoir 34 is vented to the atmosphere through passage 46 and cavity 47 in slide valve 4 to exhaust port 58. The second reduction reservoir 32 is also vented to the atmosphere by way of passage 31 and past the check valve 51 to the passage 46, through which fluid is vented from the first reduction reservoir, as previously described.

The passage 19 being connected through cavity 47 in slide valve 4 with exhaust port 58, the piston chamber 18 of piston 17 and the timing reservoir 20 will be at atmospheric pressure, so that the light coil spring 52, acting on the opposite side of piston 17 will hold said piston to its extreme position at the right, as shown in Fig. 1, with the valve 24 held unseated by the operation of the collapsible piston 21. The valve chamber 38 containing the valve 39 being connected to the atmosphere through passage 59, chamber 25, and past the open valve 24 to exhaust port 26 and the opposite side of piston 28 being also at atmospheric pressure, the spring 35 will maintain said piston in its seated position at the right, as shown in Fig. 1.

When fluid under pressure is vented from piston chamber 2 of the application valve device through pipe 57, by the operation of the speed control apparatus, the piston 3 will be shifted to application position, as shown in Fig. 2.

In this position, fluid is vented from the equalizing reservoir 12 and the piston chamber 10 of the equalizing discharge valve piston 9 to the first reduction reservoir 34, through passages 11 and 45, port 53 in slide valve 4, said port having a restricted portion 54, and passage 46, to the first reduction reservoir 34. The pressure in the equalizing reservoir 12 expanding into the first reduction reservoir 34, reduces the equalizing reservoir pressure by a predetermined amount. For example, the volume of the first reduction reservoir 34 may be such that equalization will cause a reduction of eight pounds in the equalizing reservoir pressure.

The equalizing piston 9 is then shifted by the higher brake pipe pressure acting in chamber 13, so as to unseat the discharge valve 15 and permit the venting of fluid from the brake pipe 14 so as to effect an application of the brakes. When the brake pipe pressure has been reduced to a degree slightly less than the reduction in equalizing reservoir pressure, the piston 9 will be operated to move the valve 15 to its seat, thus preventing the further discharge of fluid from the brake pipe.

Fluid thus vented from the brake pipe is not vented directly to the atmosphere as usual, but is vented to the timing reservoir 20 and the piston chamber 18 of the pilot valve mechanism by way of passage 55, a port 56 in slide valve 4, leading

to cavity 47 and thence through passage 19 to the timing reservoir 20.

As fluid discharged from the brake pipe 14 flows into the piston chamber 18 at a greater rate than it can escape through the restricted ports 48 and 49, the pressure will be built up in piston chamber 18 so as to move the piston 17 to the left, compressing the light spring 52, and causing the valve 24 to seat, as shown in Fig. 2. In this position, further movement of piston 17 to the left is opposed by the heavier coil spring 23, but the further rapid building up of pressure in piston chamber 18 and in the timing reservoir 20 by flow from the brake pipe causes a further movement of piston 17 to the left.

Upon said further movement to the left, the piston 17 moves relatively to the piston 21 owing to the collapsible character of piston 21, so that communication is established from piston chamber 18, past a reduced section of piston 17 to chamber 27, as shown in Fig. 3. The chamber 27 being open to exhaust port 26, a rapid venting of fluid from the timing reservoir 20 and the piston chamber 18 takes place so long as the discharge valve 15 remains open. When the discharge valve 15 closes after the predetermined reduction in brake pipe pressure has been completed, the pressure in piston chamber 18 and in timing reservoir 20 falls rapidly, permitting the reservoir spring 23 to move the piston 17 to the position shown in Fig. 2 in which the exhaust port piston 17 to chamber 27 is cut off.

The further reduction in pressure in piston chamber 18 and in timing reservoir 20 takes place at a slower rate by escape through the restricted ports 48 and 49 to the exhaust port 26 and when the pressure has been reduced to a degree slightly less than the value of the light spring 52, the piston 17 will be shifted to the right, so as to cause the collapsible piston 21 to unseat the valve 24, as shown in Fig. 1.

During the above operation, the fluid pressure equalized into the first reduction reservoir 34 is supplied through passage 33 to the outer seated area of piston 28 and from said area through passage 60 to valve chamber 38 and consequently when the valve 24 is opened by the operation of the piston 17, fluid is vented from valve chamber 38 through passage 59 to chamber 25 and thence past the open valve 24 to exhaust port 26. The fluid pressure acting on the outer seated area of piston 28 then operates to shift said piston to the left, as shown in Fig. 4, so that passage 33 is connected to passage 31. Fluid under pressure in the equalizing reservoir 12 and in the first reduction reservoir 34 will then equalize into the second reduction reservoir 32 and thus a second reduction in pressure in chamber 10 of the equalizing discharge valve mechanism is effected and thereby the valve 15 is operated to effect a second predetermined reduction in brake pipe pressure, corresponding with the combined volumes of the first and second reduction reservoirs.

In the open position of piston 28, the seat ring 39 seats, so as to cut off communication from valve chamber 38 to passage 59 and exhaust port 26, thus preventing a reduction of pressure in the reduction reservoirs by flow through the passage 60.

In this movement, the piston 28 engages the stem 37 of valve 36 and operates to lift said valve from its seat, so that although the piston 17 is operated to close the valve 24 during the second reduction in brake pipe pressure, the area of piston 28 which is seated by the seat ring 39 will

be maintained at atmospheric pressure by the venting of fluid from said seated area past the valve 36 to the atmospheric exhaust port 61, to provide against possible leakage of fluid under pressure from chamber 38 around the seat ring 39 to the inner seated area of the piston 28.

When the application piston 3 moves back to release position in releasing the brakes, the reduction reservoirs 32 and 34 are connected through cavity 47 in slide valve 4 with exhaust port 58, so that fluid under pressure in said reservoir is vented to the atmosphere, and opposite sides of the hold back piston 28 being at atmospheric pressure, the spring 35 returns said piston to its normal position, as shown in Fig. 1.

In the operation of the above described apparatus, the volume of the timing reservoir 20 determines the time elapsing between the first reduction in brake pipe pressure and the second reduction and in some instances it will not be necessary to provide a timing reservoir, in which case, the apparatus operates to effect the second reduction in brake pipe pressure substantially upon completion of the venting of fluid from the brake pipe in effecting the first reduction in brake pipe pressure.

In Fig. 5 is illustrated the application of the invention to the signal and speed control equipment disclosed in my prior Patent No. 1,523,462.

Fig. 5 is identical with Fig. 5 of the patent except that the application valve device of the present invention is substituted for the application valve device of the patent.

Briefly described, when a train running at high speed receives a medium speed signal indication from the track circuits, the high speed magnet 100 is deenergized thereby, while the medium speed magnet 101 is energized.

The deenergization of the high speed magnet 100 causes fluid under pressure to be vented from the piston 102 of the change speed valve device by way of passage 103, cavity 104 in slide valve 105 of the selector valve device, passage 106 and past the valve 107 to the atmosphere.

The change speed valve device is then shifted to the position shown, in which passage 57 is connected to the speed controlled valve 108 by way of passage 57, cavity 109 in slide valve 110 of the change speed valve device, passage 111, cavity 112 of the acknowledging valve device 113, and passage 114.

If the speed of the train exceeds the low speed limit, the valve 108 will be unseated by operation of the train speed controlled governor 115, so that the piston chamber of the application piston 3 is vented to the atmosphere and thereby the application valve device is shifted to application position, so that the brakes are applied as hereinbefore described, by first effecting a reduction in brake pipe pressure by venting to the first reduction reservoir and then a second reduction in brake pipe pressure by venting to the second reduction reservoir.

While the apparatus has been described as operating in connection with an automatic train speed control equipment, it will be evident that the apparatus may be employed in connection with the usual brake pipe equipment, in which case the usual engineer's brake valve is provided with ports and cavities corresponding with those in the slide valve 4, so that when the brake valve device is turned by the engineer to brake application position, the apparatus will operate the same as when the slide valve 4 is moved by piston 3 to brake application position.

Having now described my invention, what I claim as new and desire to secure by Letters Patent, is:—

1. In a fluid pressure brake, the combination with a brake pipe, of means for effecting a predetermined reduction in brake pipe pressure and means operated automatically upon completion of said predetermined reduction in brake pipe pressure for effecting a second reduction in brake pipe pressure. 5

2. In a fluid pressure brake, the combination with a brake pipe, of means for automatically effecting a predetermined reduction in brake pipe pressure and then a second reduction in brake pipe pressure upon the completion of the first 10 reduction in brake pipe pressure.

3. In a fluid pressure brake, the combination with a brake pipe, of means for effecting a predetermined reduction in brake pipe pressure and means controlled by fluid vented from the brake 20 pipe for effecting a second reduction in brake pipe pressure.

4. In a fluid pressure brake, the combination with a brake pipe, of means for effecting a predetermined reduction in brake pipe pressure, additional means for effecting a second reduction in brake pipe pressure, and means controlled by fluid vented from the brake pipe in making said predetermined reduction in brake pipe pressure for holding back the operation of said additional means. 25

5. In a fluid pressure brake, the combination with a brake pipe, of means for effecting a predetermined reduction in brake pipe pressure, additional means for effecting a second reduction in brake pipe pressure, and means operated by fluid vented from the brake pipe in making said predetermined reduction in brake pipe pressure for preventing the operation of said additional means. 35

6. In a fluid pressure brake, the combination with a brake pipe, of means for effecting a predetermined reduction in brake pipe pressure, additional means for effecting a further reduction in brake pipe pressure, and means for delaying the 40 operation of said additional means.

7. In a fluid pressure brake, the combination with a brake pipe, of means for effecting a predetermined reduction in brake pipe pressure, additional means for effecting a further reduction in brake pipe pressure, and means for delaying the operation of said additional means while the predetermined reduction in brake pipe pressure is being effected. 50

8. In a fluid pressure brake, the combination with a brake pipe, of a valve mechanism for venting fluid from the brake pipe, means for effecting the operation of said valve mechanism to produce a predetermined reduction in brake pipe pressure, and means subject to the pressure of fluid vented from the brake pipe for controlling the operation of said valve mechanism to effect a second reduction in brake pipe pressure. 55

9. In a fluid pressure brake, the combination with a brake pipe, of an equalizing reservoir, a 60 valve mechanism subject to the opposing pressures of the equalizing reservoir and the brake pipe for venting fluid from the brake pipe, a first and a second reduction reservoir, and means for first connecting the first reduction reservoir to 65 said equalizing reservoir and then the second reduction reservoir. 70

10. In a fluid pressure brake, the combination with a brake pipe, of an equalizing reservoir normally charged with fluid under pressure, a 75

- valve mechanism subject to the opposing pressures of said reservoir and the brake pipe for controlling the venting of fluid from the brake pipe, a first reduction reservoir, a second reduction reservoir, both normally at atmospheric pressure, and means for first connecting the first reduction reservoir to said equalizing reservoir and then to the second reduction reservoir.
11. In a fluid pressure brake, the combination with a brake pipe, of a valve mechanism for venting fluid from the brake pipe to effect a reduction in brake pipe pressure, valve means for effecting the operation of said valve mechanism, a valve device subject to the pressure of fluid vented from the brake pipe by operation of said valve mechanism for controlling the operation of said valve means, and a restricted communication through which fluid vented from the brake pipe to said valve device is vented to the atmosphere.
12. In a fluid pressure brake, the combination with a brake pipe, of a valve mechanism for venting fluid from the brake pipe, means for effecting the operation of said valve mechanism to produce a predetermined reduction in brake pipe pressure, valve means for effecting the operation of said valve mechanism to produce a second reduction in brake pipe pressure, and a valve device subject to the pressure of fluid vented from the brake pipe in effecting said predetermined reduction in brake pipe pressure and operative upon a predetermined reduction in fluid pressure by escape through a restricted port for effecting the operation of said valve means.
13. In a fluid pressure brake, the combination with a brake pipe, of a valve mechanism for venting fluid from the brake pipe to effect a reduction in brake pipe pressure, valve means for effecting the operation of said valve mechanism, and a valve device for effecting the operation of said valve means and operated by the flow of fluid vented from the brake pipe by operation of said valve mechanism for preventing the operation of said valve means.
14. In a fluid pressure brake, the combination with a brake pipe, of an equalizing reservoir, a valve mechanism subject to the opposing pressures of the brake pipe and the equalizing reservoir for controlling the venting of fluid from the brake pipe, a reduction reservoir, an application valve device operative to connect said reduction reservoir with the equalizing reservoir, a second reduction reservoir, valve means operative to connect said second reduction reservoir with the equalizing reservoir, and means for delaying the operation of said valve means.
15. In a fluid pressure brake, the combination with a brake pipe, of an equalizing reservoir, a valve mechanism subject to the opposing pressures of the brake pipe and the equalizing reservoir for controlling the venting of fluid from the brake pipe, a reduction reservoir, a train speed controlled application valve device operative to connect said reduction reservoir with the equalizing reservoir, a second reduction reservoir, valve means operative to connect said second reduction reservoir with the equalizing reservoir, and means for delaying the operation of said valve means.
16. In a fluid pressure brake, the combination with a brake pipe, of a valve mechanism for venting fluid from the brake pipe to effect a reduction in brake pipe pressure, valve means operative to effect the operation of said valve mechanism, a timing reservoir, a valve device subject to the pressure of fluid vented from the brake pipe to said timing reservoir by operation of said valve mechanism for controlling the operation of said valve means.
17. In a fluid pressure brake, the combination with a brake pipe, of a valve mechanism for venting fluid from the brake pipe to effect a reduction in brake pipe pressure, valve means operative to effect the operation of said valve mechanism, a valve device subject to the pressure of fluid vented from the brake pipe by operation of said valve mechanism for controlling the operation of said valve means, and an application valve device for controlling communication through which fluid vented from the brake pipe is supplied to said valve device.
18. In a fluid pressure brake, the combination with a brake pipe, of a valve mechanism for venting fluid from the brake pipe to effect a reduction in brake pipe pressure, and a valve device for controlling communication through which fluid is vented from the brake pipe by operation of said valve mechanism and operable upon the cessation of venting of fluid from the brake pipe for effecting a second operation of said valve mechanism to produce a second reduction in brake pipe pressure.
19. In an automatic train control apparatus, the combination with a brake pipe, of means for automatically effecting a reduction in brake pipe pressure in two stages, a valve device having positions for cutting said means into and out of action, and means operating upon a change in the signal indication for controlling the operation of said valve device.
20. In an automatic train control apparatus, the combination with a brake pipe, of means for automatically effecting a reduction in brake pipe pressure in two stages, and mechanism controlled in accordance with the speed of the train for rendering said means effective or ineffective.
21. In an automatic train control apparatus, the combination with a brake pipe, of means for automatically effecting a reduction in brake pipe pressure in two stages, and mechanism having a position for rendering said means ineffective and movable upon a change in the speed of the train to a position for rendering said means effective.
22. In an automatic train control apparatus, the combination with a brake pipe, of means for automatically effecting a reduction in brake pipe pressure in two stages, mechanism for cutting said means into and out of operation, a speed governor operated according to the speed of the train, and means controlled by said speed governor for controlling the operation of said mechanism.
23. In a train control apparatus, the combination with a brake pipe, of means for effecting a reduction in brake pipe pressure in two stages and a valve device operative to cut said means out of action.
24. In a fluid pressure brake, the combination with a brake pipe, of means for effecting a reduction in brake pipe pressure in two steps and a valve mechanism operative to cut said means out of action.
25. Brake applying mechanism for automatic train control systems comprising, means associated with the usual air brake system for effecting a two stage brake application which if initiated will first reduce the brake pipe pressure to a predetermined extent sufficient to bunch the slack between successive cars of a train and then a predetermined time thereafter sufficient to allow such bunching of cars will cause a further and prede-

terminated reduction in the brake pipe pressure, and means for initiating said means.

26. Brake applying mechanism for automatic train control systems comprising, means associated with the usual air-brake system which will cause a predetermined pressure reduction in the brake pipe when initiated and then after a predetermined lapse of time depending upon the speed of the train will cause a further predetermined reduction, and means for initiating said means.

27. In an automatic train control system, the combination with the usual air-brake system, of a pressure reservoir and a reduction reservoir, an application valve for normally connecting said pressure reservoir to the brake pipe and said reduction reservoir to atmosphere, said valve if operated connecting said reservoirs to each other to cause a pressure reduction in said pressure reservoir, means for venting the brake pipe when the pressure therein exceeds that of the pressure reservoir, and means for causing a further predetermined pressure reduction in said pressure reservoir after a predetermined lapse of time following the operation of said application valve.

28. Mechanism for automatically applying the brakes for train control purposes on vehicles equipped with the usual air-brake system comprising, in combination with the usual brake pipe, a pressure reservoir, a reduction reservoir, an application valve normally connecting the reduction reservoir to atmosphere and the pressure reservoir to the brake pipe, said application valve being operable to disconnect said normal connections and connect said reservoirs together, means for automatically causing a reduction in brake pipe pressure to accord with that in the pressure reservoir after the application valve has operated, a second reduction reservoir normally at atmospheric pressure, a secondary application valve for further reducing the pressure in the pressure reservoir by connecting it to the second reduction reservoir, and means for automatically operating said secondary application valve after the lapse of a predetermined interval of time following the operation of the first mentioned application valve.

29. Mechanism for automatically applying the brakes for train control purposes on railway vehicles equipped with the usual automatic air-brake system comprising, means operable to vent the brake pipe pressure to a predetermined extent in successive stages, and means having its operation dependent upon the lapse of time and automatically controlled simultaneously with said first mentioned means for determining the time intervening between said successive stages of reduction.

30. Mechanism for automatically applying the brakes of railway vehicles equipped with the usual automatic air-brake system comprising, pressure responsive means for venting the brake pipe of the air-brake system down to a predetermined pressure corresponding to that governing said means, and automatic means for varying the controlling pressure for said means in two successive stages with an intervening time interval.

31. Mechanism for automatically applying the brakes of railway vehicles equipped with the usual automatic air-brake system comprising, a pressure reservoir, a pressure operated valve for venting the brake pipe of the air-brake system down to a pressure equal to that then existing in said pressure reservoir, automatic means operable to reduce the pressure in said pressure reservoir to

a predetermined value in two successive stages with an intervening time interval.

32. In a system of automatic control for the air brakes of vehicles for train control purposes, the combination with the usual brake pipe, a pressure operated valve for venting the brake pipe, a reservoir supplying pressure to said valve, control means operable to reduce pressure in said reservoir in two successive stages, and timing means set into operation concurrently with the initiation of the operation of said control means for determining the interval of time between said stages.

33. In a system of automatic control for the air brakes of vehicles for train control purposes, the combination with the usual brake pipe, a pressure reservoir, a valve venting the brake pipe to atmosphere until its pressure corresponds with that then existing in said reservoir, a reduction reservoir normally at atmospheric pressure, means operable to connect the pressure reservoir to the reduction reservoir and thereby make a predetermined reduction in pressure in the pressure reservoir dependent upon the relative volumes of said reservoirs, a second reduction reservoir, and timing means automatically set into operation upon equalization of the pressures in the first reduction reservoir and the pressure reservoir for connecting the latter to the second reduction reservoir after the lapse of an interval of time.

34. Brake applying mechanism for automatic train control systems comprising, means operable to reduce the brake pipe pressure in the usual air-brake system to a predetermined fractional part of its original value when operated, and other automatic means for further reducing the brake pipe pressure to a predetermined fractional part of the then existing pressure, said last mentioned means being operated a predetermined time after said first mentioned means has been operated.

35. In air-brake controlling apparatus of the character described, the combination with a brake pipe, of automatic means venting the brake pipe to varying extents in succession with an intervening time interval sufficient to allow the slack between the cars of a train to be taken up.

36. In air-brake controlling apparatus of the character described, the combination with a brake pipe, of automatic means producing two successive reductions in brake pipe pressure of different values and spaced apart a period of time sufficient to allow the slack between the cars of a train to be taken up.

37. In an automatic pressure brake apparatus, a brake pipe, a reservoir, a differential valve device subject to opposing pressures from said brake pipe and reservoir and operable to permit escape of fluid from the brake pipe when the brake pipe pressure is greater than the reservoir pressure, and automatic means for obtaining periodic successive reductions in pressure in said reservoir.

38. In an automatic pneumatic brake apparatus, a brake pipe, a reservoir, a differential valve device subject to opposing pressures from said brake pipe and reservoir and operable to permit escape of fluid from the brake pipe when the brake pipe pressure is greater than the reservoir pressure, a plurality of expansion chambers, and automatic means for connecting said reservoir with the expansion chambers in succession to obtain periodic successive reductions in reservoir pressure.

39. In an automatic pneumatic brake apparatus, a brake pipe, a reservoir, a differential valve

device subject to opposing pressures from said brake pipe and reservoir and operable to permit escape of fluid from the brake pipe when the brake pipe pressure is greater than the reservoir pressure, and automatic means for obtaining, in one position, periodic successive reductions in said reservoir pressure, and, in another position, to connect the train pipe and reservoir.

40. In an automatic pneumatic brake apparatus, a brake pipe, a reservoir, a differential valve device subject to opposing pressures from said brake pipe and reservoir and operable to permit escape of fluid from the brake pipe when the brake pipe pressure is greater than the reservoir pressure, a plurality of expansion chambers, and automatic means operable, in one position, for connecting said reservoir in succession with said chambers for obtaining periodic successive reductions in reservoir pressure, and operable, in another position, for connecting the brake pipe and reservoir and opening said chambers to the atmosphere.

41. In an automatic pneumatic brake apparatus, a brake pipe, a reservoir, a differential valve device subject to opposing pressures from said brake pipe and reservoir and operable to permit the escape of pressure fluid from the brake pipe when the brake pipe pressure is greater than the reservoir pressure, an expansion chamber, and automatic means for connecting said reservoir with said chamber and operable, after said chamber is filled with fluid from the reservoir, to permit further escape of fluid from the reservoir.

42. In an automatic pneumatic brake apparatus, a brake pipe, a reservoir, a differential valve device subject to opposing pressures from said brake pipe and reservoir and operable to permit the escape of pressure fluid from the brake pipe when the brake pipe pressure is greater than the reservoir pressure, an expansion chamber, and automatic means for connecting said reservoir with said chamber and operable, after said chamber is filled with fluid from the reservoir, to permit further escape of fluid from the reservoir, said automatic means being arranged, when restored, to prevent escape of fluid from the reservoir and to connect the brake pipe and reservoir.

43. In an automatic pneumatic brake apparatus, a brake pipe, a reservoir, a differential valve device subject to opposing pressures from said brake pipe and reservoir and operable to permit escape of fluid from the brake pipe when the brake pipe pressure is greater than the reservoir pressure, an expansion chamber, automatic means for connecting said reservoir with said chamber, and automatic means operable after an interval of time after said chamber is filled with pressure fluid from the reservoir, for permitting further escape of pressure fluid from the reservoir.

44. In an automatic pneumatic brake apparatus, a brake pipe, a reservoir, a differential valve device subject to opposing pressures from said brake pipe and reservoir and operable to permit escape of pressure fluid from the brake pipe when the brake pipe pressure is greater than the reservoir pressure, a plurality of expansion chambers, automatic means for connecting the reservoir and one expansion chamber, and automatic means operable, after an interval of time after said expansion chamber is filled with fluid from the reservoir, for connecting the reservoir and other expansion chamber.

45. In an automatic pneumatic brake apparatus, a brake pipe, a reservoir, a differential valve device subject to opposing pressures from said

brake pipe and reservoir and operable to permit escape of pressure fluid from the brake pipe when the brake pipe pressure is greater than the reservoir pressure, a plurality of expansion chambers, automatic means for connecting the reservoir and one expansion chamber, and automatic means operable, after an interval of time after said expansion chamber is filled with fluid from the reservoir, for connecting the reservoir and other expansion chamber, said automatic means being arranged, when restored, to connect the reservoir and brake pipe and to connect said expansion chambers with the atmosphere.

46. In an automatic pneumatic brake apparatus, a brake pipe, a reservoir, a differential valve device subject to opposing pressures from said brake pipe and reservoir and operable to permit escape of pressure fluid from the brake pipe when the brake pipe pressure is greater than the reservoir pressure, and automatic means operable for obtaining a predetermined reduction in pressure in said reservoir, and operable, after an interval after such reduction in reservoir pressure, to obtain a further reduction in reservoir pressure.

47. In an automatic pneumatic brake apparatus, a brake pipe, a reservoir, a differential valve device subject to opposing pressures from said brake pipe and reservoir and operable to permit escape of pressure fluid from the brake pipe when the brake pipe pressure is greater than the reservoir pressure, a plurality of expansion chambers, automatic valve means for normally connecting the reservoir and brake pipe and operable for disconnecting them and connecting the reservoir and one expansion chamber, and valve means brought into operation when the chamber is filled with fluid from the reservoir and operable for connecting the reservoir and the other expansion chamber.

48. In an automatic pneumatic brake apparatus, a brake pipe, means operable by brake pipe pressure for reducing the brake pipe pressure, fluid pressure means controlling the aforesaid means in opposition to brake pipe pressure to prevent reduction in brake pipe pressure, and means for obtaining periodic successive reductions in pressure in the second named means so as to obtain periodic successive reduction in brake pipe pressure.

49. In an automatic pneumatic brake apparatus, a brake pipe, means operable by brake pipe pressure for obtaining a reduction in such pressure, fluid pressure means controlling said means in opposition to brake pipe pressure to prevent reduction in brake pipe pressure, a plurality of expansion chambers, and automatic means for connecting the second-named means with said expansion chambers in succession to obtain periodic successive reductions in the pressure opposing the brake pipe pressure, so as to obtain periodic successive reductions in brake pipe pressure.

50. In an automatic brake apparatus, a brake pipe, means operable by brake pipe pressure for the reduction of such pressure, fluid pressure means controlling said means and opposing brake pipe pressure to prevent reduction in brake pipe pressure, an expansion chamber, automatic means for connecting the second-named means and said expansion chamber for a predetermined reduction in the pressure opposing brake pipe pressure so as to obtain a predetermined reduction in brake pipe pressure, and automatic means operable after an interval of time following the filling of said chamber with pressure fluid,

for permitting further escape of pressure fluid from the second named means to obtain a further reduction in brake pipe pressure.

51. In an automatic pneumatic brake apparatus, a brake pipe, means operable by brake pipe pressure for the reduction in said pressure, fluid pressure means controlling said means and opposing brake pipe pressure to prevent reduction in brake pipe pressure, signal and speed control means controlling the second named means and operable under a predetermined signal impulse and above a predetermined speed for obtaining a limited reduction in pressure in the second named means for obtaining a corresponding reduction in brake pipe pressure, and automatic means operable, after an interval of time following such pressure reduction, for permitting further escape of pressure fluid to obtain a further reduction in brake pipe pressure.
52. In an automatic pneumatic brake apparatus, a brake pipe, automatic means controlled by a signal impulse and vehicle speed and operable upon receipt of a predetermined signal impulse and above a predetermined vehicle speed for obtaining a limited reduction in brake pipe pressure, and automatic means operable for obtaining a further reduction in brake pipe pressure after an interval following the aforesaid reduction in brake pipe pressure.
53. In a fluid pressure brake, the combination with a brake pipe, of two reduction reservoirs, means operated upon a venting of fluid under pressure into either reservoir for effecting a reduction in brake pipe pressure, one reservoir being connected for venting purposes only after the venting of fluid from the brake pipe due to venting of fluid under pressure to the other reservoir has ceased.
54. In a fluid pressure brake, the combination with a brake pipe, of a first reduction reservoir, a second reduction reservoir, and means for first venting fluid under pressure to the first reservoir to effect a reduction in brake pipe pressure and then to the second reduction reservoir to effect a second reduction in brake pipe pressure, said reservoirs being connected the one to the other only after the first reduction in brake pipe pressure has been completed.
55. In a fluid pressure brake, the combination with a brake pipe, of a first reduction reservoir, a second reduction reservoir initially out of communication with the first reservoir, and means for first venting fluid under pressure to the first reservoir to effect a reduction in brake pipe pressure and then only after the first reduction ceases to the second reduction reservoir to effect a second reduction in brake pipe pressure.
56. In a fluid pressure brake, the combination with a brake pipe, of a first reduction reservoir, a second reduction reservoir, a valve device having a position in which the first reduction reservoir is connected to the second reduction reservoir, and valve means having one position for connecting one side of said valve device to the atmosphere and another position in which fluid under pressure is supplied directly to said valve device.
